ADJUSTABLE BRACKET CONSTRUCTION

Mary B. McDougall, Pasadena, Calif.

Application May 24, 1935, Serial No. 23,281

2 Claims. (Cl. 248—257)

This invention relates to supports for rollers such as those upon which maps or window shades are commonly mounted.

One of the objects of this invention is to provide such supports which may be easily adjusted to accommodate rollers of varying length and which are held against accidental displacement from their adjusted position.

Another object of the invention is the provision of such supports wherein the fixed member and movable members are of simple form and may be readily produced at low cost.

Another object of the invention is the provision of brackets adjustably mounted on a suitable support, such as a molding, said brackets being so constructed that they are held in positive adjusted position by the aid of a simple and inexpensive construction.

This invention possesses many other advantages, and has other objects which may be made more easily apparent from a consideration of several embodiments of the invention. For this purpose there are shown a few forms in the drawing accompanying and forming part of the present specification. These forms will now be described in detail, illustrating the general principles of the invention; but it is to be understood that this detailed description is not to be taken in a limiting sense, since the scope of this invention is best defined by the appended claims.

Referring to the drawing:

Figure 1 is an isometric view showing one of the improved supports mounted on a wall with one end of a roller in place in the movable bracket;

Figs. 2 and 3 are sections on an enlarged scale as seen on correspondingly numbered planes of Fig. 1;

Fig. 4 is a front elevation, also on an enlarged scale, of the roller and support of Fig. 1;

Fig. 5 is a cross-sectional view of a slightly different form of the fixed member;

Fig. 6 is an isometric view of a modified form of the movable bracket; and

Fig. 7 is an isometric view of another modified form of the movable bracket.

Referring more particularly to the drawing, a roller 8 may have a map, chart, or the like, 9 carried on it. A supporting pintle 10 extends from one end of the roller and fits in a suitable opening 11, such as a slot or aperture formed in a projecting ear 12 on the movable bracket 13. A similar supporting pintle and bracket will, of course, be provided at the opposite end of roller 8.

If roller 8 is a spring-roller, such as is common-

ly used, the supporting pintle 10 at one end will be square or flat and the opening 11 shaped correspondingly.

Bracket 13 as will be noted from an inspection of Fig. 2 is of an inverted U or channel shape, having an outside leg 14 upon which the ear 12 is formed, and an inside leg 15. The inner leg is longer than the outer leg and reduced in width, terminating in the depending extension 16. The fixed or stationary member 17 may be formed of a strip or narrow plate of metal 18 having a bottom flange or inturned leg 19. It may extend continuously between the brackets and the desired distance beyond each, or it may be only a short section at each bracket of sufficient length to permit the desired range of adjustment.

Member 17 is mounted on a cooperating moulding or plate 20 which may be made of wood. Countersunk head wood screws 21 can be provided with separators 22 serving to hold the strip 18 in spaced relationship therewith (Fig. 3). This forms an upright U or channel 24 upon the upper edge of the outer leg of which the bracket 13 is adapted to rest. The bottom flange 19 has cut out portions or slots 23, adapted to receive the extension 16 (Fig. 4). This of course must be of such length as to extend slightly through the opening 23 when bracket 13 rests on the edge of leg 18. Molding 20 is secured on wall 25 in any convenient manner.

It will be plain from an inspection of the drawing that bracket 13 may be easily shifted longitudinally along the stationary member by raising it a short distance to bring extension 16 out of opening 23. As legs 14 and 15 of the movable bracket continue to embrace the leg 18, this adjustment is rendered easy. The fineness of the adjustment will depend on the spacing of the openings or slots 23. The weight of the roller etc., resting on the bracket will serve to hold extension 16 in its opening, thus preventing accidental displacement of the bracket 13.

In Fig. 5 is illustrated a different form of support for the bracket 13. In this form, a U-shaped metal strip 26 provides the channel 24, the outer leg 27 functioning as leg 18 in the previously described form, and the inner leg 28 being secured directly to the wall 25 as by screws 29. Thus the wood molding 20 is eliminated. Openings 30 are provided in the bottom of the channel to engage extension 16.

Fig. 6 shows a modified form of bracket 13 having a pair of openings 11, whereby two rollers may be supported, one behind the other. By increas-

ing the length of ear 12 more openings may be provided to support additional rollers, if desired.

Fig. 7 shows another modification of bracket 13 in which ear 12 previously described is formed 5 as a hook 31 from which drapes or the like may be hung. Of course, other forms of hanging attachments could be utilized.

I claim:

1. In a device of the character described, a 10 supporting trough open at the top and having spaced apertures in the bottom of the trough in combination with a sheet metal bracket comprising a folded U-shaped portion, the legs of said U-shaped portion being adapted to straddle one 15 side of the trough, the inner leg being adapted to extend into any one of said trough apertures,

said bracket also having an object supporting member extending perpendicularly to the plane of the U-shaped portion.

2. In a device of the character described, an 5 elongated member having an angled extension at its bottom, said extension having a series of spaced notches, in combination with a sheet metal bracket comprising a folded U-shaped portion, the legs of said U-shaped portion being adapted to straddle said member, the inner leg being 10 adapted to extend into any one of said notches, said bracket also having an object supporting member extending perpendicularly to the plane of the U-shaped portion.
